UNITED STATES PATENT OFFICE.

ANDREW LEESEKAMP, OF ANAMOSA, IOWA.

CASK COVER.

1,417,845.

Specification of Letters Patent. Patented May 30, 1922.

Application filed August 30, 1921. Serial No. 496,990.

To all whom it may concern:

Be it known that I, ANDREW LEESEKAMP, a citizen of the United States, residing at Anamosa, in the county of Jones and State 6 of Iowa, have invented certain new and useful Improvements in Cask Covers, of which the following is a specification, reference being had therein to the accompanying drawings.

10 This invention relates to a cask cover, and the object is the construction of a simple and efficient device for covering the top of a cask or barrel, and which device can be quickly placed upon the cask or removed 15 therefrom, so that the operator can easily have access to the contents of the cask.

With this and other objects in view, my invention comprises certain novel combinations, constructions and arrangements of 20 parts as will be hereinafter described, illustrated in the accompanying drawings, and more particularly pointed out in the appended claims.

In the drawings:

25 Figure 1 is a top plan view of the device in an open position, while

Figure 2 is a top plan view, showing the same in a closed position.

Figure 3 is a view in elevation, taken on 30 line 3—3, Fig. 2, and looking in the direction of the arrows.

Figure 4 is a transverse, vertical, sectional view of the device, showing the fabric cover thereon.

35 Referring to the drawings by numerals (dotted lines) 1 designates the cask or barrel. The device comprises a resilient piece 2 of metal of a split ring-like structure, and this body 2 is provided with an outwardly-projecting portion 3 to which is attached a strap-iron hinge 4, which hinge 4 is usually fastened by nails or tacks (not shown) to the cask 1; this hinge is provided with apertures 5 through which the ordinary nails or 45 tacks extend into the cask.

The ends of the ring-like body 2 are formed into loops 6 and 7. In loop 6 is positioned elongated link 8. Curved lever-handle 9 is pivotally mounted, at its inner end, in the loop 7, and the grip 10 is formed upon the outer end of the handle 9. A plurality of sockets 11 are formed on the inner edge of the handle 9, and these sockets extend inwardly toward the inner end of the 55 handle, so that the outer end of the link 8 will be more securely retained in the handle when

the device is in its closed position, as shown in Fig. 2; by forming the sockets so that they extend slightly inwardly toward the inner ends of the handle, these sockets produce a "hook" structure, tending to prevent the link 8 from being displaced out of a socket when in its closed position, Fig. 2. To very positively prevent a link from jumping out of a socket, I employ a curved 60 plate 12 laid against the outer edge of the handle, and I fasten the plate over sockets 11, by detachable bolts 13; by unscrewing one bolt 13, the plate can be swung upon the other bolt to one side of the handle, permitting the link 8 to be moved from a seated 65 position.

Integral with the ring-like body 2 is an apertured lug 14 and this lug is seated in an aperture or slot 15 formed in the handle when the device is in a closed position, Fig. 2. Through registering apertures 16 extends a fastening pin or bolt 17, positively fastening the handle 9 in a closed position against the ring-like body 2.

70 A suitable fabric covering 18 is wrapped or placed over the device (Fig. 3) for preventing foreign objects or insects from entering the cask or barrel, upon which my device is placed, when the device is in a 75 closed position upon said cask.

The device can be applied to different size barrels or casks, since, by placing the link 8 in different sockets 11, the size of the device can be controlled so as to adapt it for 80 use on different size receptacles, such as casks or barrels, or the like.

While I have described the preferred embodiment of my invention, and have illustrated the same in the accompanying drawings, certain minor changes or alterations 85 may appear to one skilled in the art to which this invention relates, during the extensive manufacture of the same and I, therefore, reserve the right to make such 90 alterations or changes as shall fairly fall 95 within the scope of the appended claim.

What I claim is:

In a device of the class described, the combination of a springy, split, ring-like 105 body provided intermediate its end with an outwardly-extending portion, a strap hinge on said outwardly-extending portion, said body having its ends formed into loops, an elongated link mounted in one of said loops, 110 a curved lever-handle pivotally mounted in the other loop, an apertured lug formed

2
upon the body contiguous to said loop with
the lever-handle, said lever-handle provided
with a plurality of sockets in its inner edge,
said sockets extending inwardly toward the
inner end of the lever-handle, said elongat-
ed link positioned in one of said sockets, a
curved plate positioned over said sockets
and extending through the elongated link
and bearing against the lever-handle, bolts
extending through said plate and into said
lever-handle detachably securing the plate

to said lever-handle, said lever handle pro-
vided with a slot receiving said lug, and
fastening means extending through the slot-
ted portion of the lever-handle and a lug 15
fixedly holding the lever-handle in a closed
position upon the ring-like body, substan-
tially as shown and described.

In testimony whereof I hereunto affix my
signature.

ANDREW LEESEKAMP.
